UNITED STATES PATENT OFFICE.

GEORG RENNER, OF DUSSELDORF, GERMANY.

FLUSH-CISTERNS.

1,386,948.

Specification of Letters Patent.

Patented Aug. 9, 1921.

Application filed September 10, 1919. Serial No. 323,042.

To all whom it may concern:

Be it known that I, GEORG RENNER, a citizen of the German Republic, and resident of 137 Bilker Allee, Dusseldorf, Germany, have 5 invented certain new and useful Improvements in Flush-Cisterns for which I have filed applications in Germany, Mar. 8, 1914; Austria, June 17, 1918; Norway, June 4, 1919; Sweden, June 5, 1919; France, June 10 7, 1919; Switzerland, July 19, 1919; Finland, July 21, 1919; Belgium, July 31, 1919; Gr. Britain, Nov. 7, 1919; Italy, May 10, 1920; Luxembourg, Aug. 4, 1920; Holland, Sept. 15, 1920; Czechoslovakia, Apr. 23, 1921, of 15 which the following is a statement.

The present invention relates to a flushing cistern, which, when not in use, is free of water, and on which the lock for the lever controlling the supply and discharge valves 20 is released by a float. The feature of the present invention consists in the discharge valve being disposed in the form of a tilting siphon on the bottom of the cistern tank; this siphon-valve is opened and closed by means 25 of the flushing lever, which at the same time controls the supply valve; to this flushing lever is further pivoted the float lever.

In the accompanying drawing a cistern according to the present invention is shown 30 in longitudinal section in Figures 1 and 5, respectively, while Fig. 2 is a plan of a portion of the tank. Fig. 3 illustrates the supply valve with a piece of the control lever and of the float lever, partly in section, 35 partly in elevation; Fig. 4 is a plan to Fig. 3, Fig. 6 is the lock member in combination with the float lever and the control lever in side elevation in another position, and Fig. 7 is a front elevation thereof; Fig. 8 is a 40 plan of the locking member with only a piece of the float lever.

The discharge valve has the form of a siphon tube *d*. It is provided with trunnions *e* which rest in bearings *w* provided on the 45 discharge tube *a* of the cistern tank *b*. When in an upright position this siphon tube bears with its jointing surface *c* tightly against the mouth of the discharge tube *a*. Cast in one piece with said siphon tube *d* is a 50 bracket *f*, on which rests the control lever *g*. This control lever *g* is pivotally fitted on a pivot *h* on the housing *i* of the supply valve and engages with an arm *l* projecting therefrom into a slot *m* in the valve plug *m*, to 55 which is fitted a rubber disk *m* for closing the supply orifice *i*. On the valve housing

i is disposed a supporting nose *n* on which the part *p* rests when in operative position; this part *p* is pivoted by means of pin *o* to the control lever *g*. To said part *p* is fitted 60 the float lever *q*. The extension of the control lever *g* beyond its pivot *h* acts as an operating lever to which the pull chain may be attached.

When not in use the cistern will be empty 65 and the tilting siphon tube will be open. The part *p* of the float lever *q* has slipped off the nose *n*, the supply orifice *i* is closed and the counterpoise *u* on the control lever is in its lowest position (Fig. 5). When as by a 70 chain (not shown) the extension *s* is pulled down, the control lever *g*, the float lever *q* and the part *p* are lifted until the latter bears with its corner *p* on the nose *n*; at the same time the valve plug *m* is pushed back 75 by the arm *l* and the supply orifice *i* is opened. The offset *h* of the control lever *g* allows of the siphon tube *d* being moved into a vertical position so that the discharge tube is closed. (Fig. 1). As the supply valve is 80 open, water will flow through orifice *t* into the cistern tank *b*. As it rises therein the water will lift the float ball *r* and thereby move the float lever and the thereto attached part *p* until it slips with its corner *p* from 85 nose *n*, so that part *p* and with it control lever *g* lose their support and sink down. On the weight *u* on the control lever *g* thus 90 sinking, the offset *h* strikes against the ledge *f*, and on further sinking it tilts the siphon tube *d* over, so that the discharge tube *a* is opened, while at the same time the valve disk *m* is pressed by arm *l* tightly against the supply orifice *i* and the further entrance 95 of water is shut off.

As the float lever *g* is somewhat offset, the float ball *r* may be adjusted to a proper position by bending the said lever. The siphon tube may be readily lifted out from the tank *b* as the bearings *w* for the trunnions are 100 open at the top.

I claim:

1. A flush-cistern, which is free of water when not in use, consisting of a cistern tank, a supply valve, means for opening said valve 105 by hand, a weighted lever adapted to close said valve, a discharge valve, adapted to be opened by said weighted lever on the supply valve being closed, and to be closed on the supply valve being opened, means for supporting the weighted lever when in raised position and the supply valve is open, a 110

float within said tank, adapted to disengage the said support of the weighted lever when the water level in the tank is high.

2. A flush-cistern, which is free of water when not in use, consisting of a cistern tank, a supply valve fitted thereto, a lever for operating said supply valve, a pull member on said lever for opening said valve, a weight on said lever for closing said valve, 10 a tilting discharge valve, said discharge valve adapted to be seated by said lever on the mouth of the discharge tube when said supply valve is opened, and to be tilted over

when said supply valve is closed, a lever with a float, pivotally fitted to said operating lever, a nose for supporting said float lever with said operating lever when the supply valve is open, until the float has been lifted by the water in the tank so far that the lever slips off its supporting nose, whereupon the weight pulls down the lever, and thereby closes the supply valve and opens the discharge valve.

In testimony whereof I affix my signature.

GEORG RENNER.
